UNITED STATES PATENT OFFICE.

FREDERICK W. HOWELL, OF BUFFALO, NEW YORK, ASSIGNOR TO MARGARET T. HOWELL, OF SAME PLACE.

COCKLE-SEPARATOR.

SPECIFICATION forming part of Letters Patent No. 331,061, dated November 24, 1885.

Application filed September 20, 1883. Serial No. 106,907. (No model.)

To all whom it may concern:

Be it known that I, FREDERICK W. HOWELL, of the city of Buffalo, in the county of Erie and State of New York, have invented new 5 and useful Improvements in Cockle-Separators, of which the following is a specification.

This invention relates to an improvement in that class of grain-separators in which the separation of the different kinds of grain is effected by a rotating cylinder provided on its 10 inner surface with cells or indentations, in which the small grains lodge, while the large grains roll back, and more particularly to such a separator in which the grain to be separated is fed upon the inner surface of the separator 15 simultaneously throughout the length of the cylinder. A machine of this kind is described in Letters Patent of the United States No. 266,258, granted to me October 17, 1882, to 20 which reference is here made for a full description thereof.

The object of this invention is to supply the grain to be separated more directly to the cylinder than heretofore, and to render the 25 feed mechanism more compact and reliable; also to improve the construction of the machine generally; and my invention consists of the improvements in the construction of the machine, which will be hereinafter fully set 30 forth, and pointed out in the claims.

In the accompanying drawings, consisting of five sheets, Figure 1 represents a front elevation, and Fig. 2 a rear elevation, of my improved separator. Fig. 3 is a longitudinal 35 sectional elevation of the same. Fig. 4 is a cross-section of the machine, on an enlarged scale. Fig. 5 is a fragmentary cross-section on a still larger scale. Fig. 6 is a horizontal section in line $x-x$, Fig. 4. Fig. 7 is a horizontal section of the front supporting-wheels. Fig. 8 is a horizontal section of the rear supporting-wheels. Fig. 9 is a top plan view of 40 one of the knockers. Fig. 10 is a perspective view of one of the end shields. Fig. 11 is a perspective view of one of the brackets.

The same letters of reference refer to like parts in the several figures.

A represents the stationary frame of the machine, and B the separating-cylinder supported in the frame A upon rollers $b-b'$, so that the cylinder can be rotated about its axis. The cylinder B is constructed on its inner surface with cells or indentations, whereby 45 the different kinds of grains are separated in

a well-known manner, the small grains being 55 received in the cells or indentations and elevated thereby as the cylinder rotates, while the large grains are rejected and roll back. The cylinder B is provided in its side with a longitudinal opening or slot, c , through which 60 the large grains which are not elevated by the cells are finally discharged from the cylinder.

D represents the feed-hopper, which is arranged lengthwise in the cylinder, near the lowest point of the same; and d is the feed- 65 roller, whereby the escape of the material from the feed-hopper is regulated in connection with a feed slide or gate, d' , which is made adjustable with reference to the feed-roller by rack-bars d^2 and gear-wheels d^3 , meshing therewith. 70

d^4 represents a shield secured to the inner side of the feed-hopper, and projecting over the feed-slide d' , to prevent the grain from entering behind the feed slide and obstructing its movements.

E represents a bucket arranged between the feed-hopper and the lower portion of the cylinder B, for the purpose of receiving the grain which is gradually discharged from the feed-hopper by the rotation of the feed-roller, and 80 discharging such grain at the proper time upon the lower portion of the cylinder. The bucket E consists of two plates, e and e' , which rest against each other at or near their lower edges and diverge upwardly to receive the material discharged from the feed-hopper. The plate e is pivoted at or near its upper end, as shown at e^2 , either to the feed-hopper, as represented in the drawings, or to some other stationary part of the machine. The plate e' is 85 pivoted near its lower edge, as shown at e^3 , to the end plate F of the feed-hopper, secured to the stationary frame of the machine. The plates e and e' are connected by links $f-f'$ in such manner that when the plate e is swung upwardly on its pivots from the position represented in full lines in Fig. 5 to the position 90 represented in dotted lines, the plate e' is swung on its pivots from the position represented in full lines to the position represented in dotted lines, whereby the lower edges of the plates are separated and the plate e' placed in an inclined position, which causes the grain contained in the bucket to be discharged into the cylinder. This movement of the plates is 95 effected by cams or projections g , which are secured to the ends of the cylinder and come in contact with rollers g' , attached to the plate

- e. The studs or arbors of the rollers g' project through curved slots g^2 , formed in end plates or shields k^5 . When the cams g have cleared the rollers g' , the plates e are returned to their former position by gravity, the period of time during which the plates are separated being sufficient to permit the discharge of the accumulated grain from the bucket. The cams g are so located on the cylinder that the bucket 10 will be opened after the opening c has passed by the bucket, so that the grain is discharged from the bucket upon that portion of the cylinder next adjacent to and in rear of the opening c . The cams g are formed on the inner 15 edges of rings g^3 , which are secured to the ends of the cylinder B . The rings g^3 are provided on their outer sides with V-shaped rims g^4 , which run in the grooves of the supporting-rollers b b' . The grain may be supplied to the 20 feed-hopper by spouts extending through one or both of the open ends of the cylinder D ; but in machines of large capacity I prefer to deliver the grain into a preliminary grading-reel, H , which is arranged longitudinally 25 within the cylinder B above the feed-hopper. The reel H is so clothed that the small grains—such as cockle-seeds and small wheat or other grain—pass through the meshes of the reel and fall into the feed-hopper D , while the 30 large wheat or other grain passes through the reel and is discharged from the tail end of the reel into a hopper, h , the reel being slightly inclined to cause the grain to move longitudinally through the reel.
- 35 h' represents the shaft of the reel, which is supported in bearings h^2 , the latter being attached by adjusting-screws h^3 to hangers h^4 , which are secured to the stationary frame A . By means of the screws h^3 the inclination of the reel can be regulated. The adjusting-screws 40 are moved by screw-nuts h^5 , resting upon the lower portions of the hangers h^4 .
- H' represents a driving-pulley secured to the shaft h' .
- 45 i represents a longitudinal roller which bears against the outer side of the reel H , or is arranged in close proximity to the outer surface of the reel, and serves to press inwardly and detach any grains which may have lodged in 50 the meshes of the reel, thereby keeping the reel clear. The roller i is supported in bearings i' , which are attached to the upper ends of the adjusting-screws h^3 , so that the roller takes part in the movements of the reel in 55 adjusting the pitch of the latter. The roller i is preferably constructed of a metallic shaft or core covered by a tube of rubber or other elastic or flexible material.
- 60 J represents the inclined board, which receives the small grain which has been elevated by the cells of the cylinder B . This board is preferably composed of an upper and lower portion, the former being made adjustable by gear-racks j and pinions j' , and provided at its upper edge with a roller, j^2 , as described in my above-mentioned Letters Patent. The roller j^2 is supported in hook-shaped bearings j^3 , open

at their lower sides and secured at suitable distances apart, so that the roller can be readily removed from its bearings upon lifting the 70 upper end of the inclined board from the cylinder B .

K represents the screw-conveyer, arranged in a trough, k , at the foot of the inclined board J , so as to receive the cockle and small 75 seeds which escape from the latter.

k' represents a curved plate arranged over the lower portion of the cylinder on its ascending side, preferably concentric therewith and in such close proximity to the cylinder 80 that the grain discharged from the bucket E will be spread by the plate k' and distributed in a thin layer over the cylinder, thereby preventing the grain from revolving in a large mass on the ascending side of the cylinder, 85 which would interfere with the proper separation. The plate k' is secured with its ends to the end plates or shields, k^5 . The upper end of the plate k' is provided with an upwardly-projecting flange, k^2 , which prevents 90 the grain elevated by the cylinder from falling on the plate.

Instead of constructing the plate, as shown, it may be constructed of a series of bars.

L represents a screw-conveyer, and l the trough of the same, arranged below the cylinder for the reception of the grain which is discharged through the opening c . The trough l is provided with an inclined extension, l' , extending upwardly under the ascending side 100 of the cylinder, and supported on its outer edge by castings l^4 , which extend around the supporting-roller and form close joints around the same. The extension l' receives the material which escapes through the opening c as 105 the cylinder rotates, and conducts such material to the trough l .

m represents an outwardly-projecting lip or flange formed along the rear edge of the opening c , for the purpose of catching any small 110 grain which may lodge on the roller j^2 , and return such grain into the cylinder.

N N are plates cast on the lower horizontal cross pieces, a , of the frame A , and extending both below and above said cross-pieces. The end plates F of the feed-hopper D are secured to the inner sides of the end plates N by bolts n . The plates N are provided with openings closed by caps n' n^2 , which are secured to the outer sides of the plates N , and in which the feed-roller d is journaled.

n^3 represents the driving-pulley, mounted on the shaft of the feed-roller d . The latter extends through the end plate F next the driving-pulley n^3 , so that upon detaching the cap n' between the pulley n^3 and the plate F the feed-roller can be drawn out of the feed-hopper through the openings in the plates F and N . After the feed-roller has been withdrawn and the end plates F have been detached from the plates N , the feed-hopper can be lifted out from between the plates N . The latter are provided with openings arranged opposite the ends of the conveyer K , and made

of sufficient size to permit the conveyer to be passed through the same. These openings are closed by caps o o' , which are secured to the outer sides of the plates N, and in which 5 the conveyer-shaft is journaled.

o^2 represents the driving-pulley secured to the shaft of the conveyer K near the cap o .

o^3 represents a spout formed on the cap o' for the discharge of the grain from the conveyer-10 trough k . The ends of the conveyer-trough k are secured to flanges k^3 , cast on the inner sides of the shields k^5 , arranged in the same vertical planes with the end plates F of the feed-hopper. Bolts k^4 extend through the caps 15 o o' , shields k^5 , and into the flanges k^3 , so that upon removing these bolts the caps, the shields, and the conveyer-trough k can be removed. The shields k^5 extend upwardly at both ends 20 of the cylinder, along the lower portion of its ascending side, for a sufficient distance to prevent the grain contained in the cylinder from escaping over the ends thereof. The lower portions of the shields k^5 and the end plates F of the feed-hopper are arranged at a short distance 25 from the inner sides of the plates N, to leave spaces through which the rings g^3 and cams g move.

Upon detaching the cap o next the driving-pulley o^2 from the plate N the conveyer can 30 be removed, and upon detaching the shield k^5 from the plates N the trough and connecting parts can be removed.

p^1 are openings formed in the lower depending portions of the plates N, opposite the 35 screw-conveyer L, and P P' are caps closing these openings and secured to the outer sides of the plates N.

p^2 is the driving-pulley secured to the shaft of the conveyer L on the outer side of the cap 40 P, and p^3 represents a discharge-spout formed with the cap P'. The trough l of the conveyer L is secured to the inner sides of the plates N. Upon detaching the cap P from the plate N the conveyer L can be withdrawn through the 45 opening p . The conveyer-trough l is provided at its ends with flanges l^2 , which are secured to the inner sides of the plates N by the same bolts, l^3 , which secure the caps P P' to the plates N, so that upon detaching the caps the 50 conveyer-trough is also detached from said plates.

q is a spout which connects the hopper h with the discharge-spout p^3 , so that the large grain discharged from the reel is united with the 55 large grain escaping from the conveyer L.

The rollers b at the head of the machine are secured to shafts r , which are supported in bearings r' , formed on the frame A.

r^2 are driving-pulleys mounted on the shafts 60 r in the same vertical plane with the pulleys n^3 o^2 p^2 . The rollers b' at the tail end of the machine are mounted loosely on studs or arbors r^3 , secured to the frame, so that these rollers can adjust themselves on their arbors 65 lengthwise, when the two rings at the ends of the cylinder B are not strictly parallel with each other.

R represents an endless drive-chain, running around the pulleys H', o^2 , n^3 , r^2 , and p^2 , as clearly shown in Fig. 1, said pulleys being constructed in the form of sprocket-wheels to engage with the drive-chain. 70

When the machine is not provided with a reel, H, the drive-chain is placed over the upper side of the pulleys o^2 n^3 , and the flight of 75 the conveyer K and the arrangement of feed-slide in the feed-hopper are reversed to correspond with the reversed direction in which the conveyer K and the feed-roller d are rotated in this case. 80

The frame is composed of end frames, A', and longitudinal connecting-pieces A² A³. The latter are constructed of angle-irons, and the upper connecting-pieces, A², are secured to the end frames by brackets S. The upper 85 sides of the brackets are fitted in the angles of the connecting-pieces A², and secured to the latter by bolts s, and the ends of the brackets are fitted against the inner sides of the end frames, A', and secured to the latter by bolts 90 s'. Upon removing the bolts s' the connecting-pieces A² and the brackets S secured thereto can be detached from the end frames, when the cylinder B can be lifted out from between the end frames. The lower connecting-pieces, 95 A³, are secured at their ends to angular castings S', which are secured to the inner sides of the end frames, A'.

T represents knockers mounted loosely on a horizontal shaft or rod, t, arranged lengthwise 100 over the cylinder and provided with depending arms t', which are operated by cams or inclines t'', secured to the cylinder. The depending arms t' are made separate from the knockers and connected therewith by interlocking teeth t³, formed on the contiguous faces of the hubs of the knocker T and arm t', as represented in Fig. 9, so that the position of the depending arm with reference to the knocker can be changed by disengaging the 105 arm from the knocker and turning said parts with reference to each other, thereby changing the stroke of the knocker accordingly. The knockers are provided with springs t⁴. The knocker is preferably faced with rubber 110 or other elastic material. The springs t⁴ raise the knockers from the cylinder after the blow has been struck, and prevent the knockers from dragging on the cylinder. 115

The grain to be separated is fed into the reel 120 H, which effects a separation of the large grain from the small grain, the latter, consisting of cockle-seeds, broken wheat, and small wheat, passing through the meshes or perforations of the reel into the feed-hopper D, while 125 the large grain escapes over the tail of the reel into the hopper h. The small grain is delivered from the feed-hopper by the feed-roller into the bucket E, in which the grain accumulates until the bucket is opened by the cams 130 g. This takes place as soon as the opening c of the cylinder has passed the point or lower end of the bucket. The grain contained in the bucket is thereby discharged upon that

portion of the cylinder which follows inwardly after the opening *c*. The grain resting upon the inner surface of the cylinder is carried by the rotation of the latter under the plate *k'*, which levels and spreads the grain. The cockle and other small seeds and grains lodge in the cells of the cylinder, and the large grain rolls back. The cockle and small grain are elevated by the rotation of the cylinder and deposited upon the inclined board *J*, from which it passes into the conveyer-trough *k*, whence it is discharged by the conveyer *K* through the spout *o'*. The large grain remains in the cylinder until the opening *c* reaches the lowest point of the cylinder, when the large grain is discharged through the opening *c* into the conveyer-trough *l*.

It will be seen that the grain to be separated is delivered more directly into the cylinder than in machines having the feed-hopper on the outside of the cylinder, and that no grain can pass from the feed-hopper to the passages through which the separated grain is removed without having first been subjected to the separating action of the cylinder. Furthermore, the grain is delivered upon the inner cylinder surface with very little movement, so that the entire inner surface of the cylinder is rendered available for the separating operation, while in machines having the feed-hopper on the outside of the cylinder the grain enters with considerable velocity and passes over a portion of the inner cylinder-surface at too great a speed to permit of the proper separation. The parts of the machine are so constructed that they can be readily put together in setting up the machine and easily separated when required for making repairs.

I claim as my invention—

- 40 1. The combination, with a separating-cylinder provided with cells or indentations in its inner surface and a discharge-opening in its side, of a feed-hopper arranged lengthwise in the cylinder, a bucket arranged in the cylinder below the feed-hopper and delivering the material directly upon the separating-surface of the cylinder at intervals, and an inclined catch-board, whereby the material elevated in the cells or indentations is collected, substantially as set forth.
- 45 2. The combination, with the cylinder *B* and feed-hopper *D*, of the bucket *E*, composed of the pivotal plates *e' e'*, and connecting links *f' f'*, substantially as set forth.
- 50 3. The combination, with the stationary frame and a cylinder having cells or indentations formed in its inner surface, of end shields, *k'*, secured to the stationary frame of the machine, substantially as set forth.
- 55 4. The combination, with a cylinder having cells or indentations formed in its inner surface, of a stationary plate, *k'*, arranged over the ascending inner surface of the cylinder, whereby the grain is evenly distributed, substantially as set forth.
- 60 5. The combination, with a separating-cylinder, of a feed-hopper arranged lengthwise

in the cylinder and a preliminary separating-screen arranged in said cylinder above said feed-hopper, substantially as set forth. 70

6. The combination, with a separating-cylinder having cells or indentations on its inner surface, of a rotating screen arranged in said cylinder and a longitudinal feed-hopper arranged in said cylinder underneath the rotating screen, substantially as set forth. 75

7. The combination, with the cylinder *B*, of a stationary frame having end plates *N N*, a feed-hopper, *D*, having end plates *F F*, secured to the plates *N N*, and shields *k'*, secured to the plates *N N*, substantially as set forth. 80

8. The combination, with a rotating screen, of adjustable bearings in which the shaft of the screen is supported and a roller arranged in close proximity to the outer surface of the screen and supported in the adjustable bearings of the rotating screen, substantially as set forth. 85

9. The combination, with the cylinder *B*, provided with cams *g*, and stationary frame, 90 of the feed-hopper *D*, bucket *E*, provided with rollers *g'*, and end plates *k'*, having curved slots *g''*, substantially as set forth.

10. The combination, with the cylinder *B*, of driving-rollers *b*, supported in fixed bearings and supporting-rollers *b'*, made lengthwise movable with reference to the cylinder, substantially as set forth. 95

11. The combination, with the cylinder *B* and stationary frame having plates *N N*, of the feed-hopper *D*, having end plates *F*, feed-roller *d*, and caps *n' n''*, substantially as set forth. 100

12. The combination, with the cylinder *B* and stationary frame having plates *N N*, of the conveyer *K*, trough *l*, and caps *o' o''*, substantially as set forth. 105

13. The combination, with the cylinder *B* and stationary frame having plates *N N*, of the conveyer *L*, trough *l*, and caps *P' P''*, substantially as set forth. 110

14. The combination, with the cylinder *B*, of the end frames, *A' A'*, longitudinal connecting-pieces *A''*, and brackets *S*, substantially as set forth. 115

15. The combination, with the cylinder *B*, of a knocker, *T*, and a depending actuating-arm, *t'*, provided, respectively, with interlocking portions, whereby the position of the actuating-arm with reference to the knocker can be changed, substantially as set forth. 120

16. The combination, with the cylinder *B*, of the supporting-roller *b*, reel *H*, feed-roller *d*, and conveyers *K L*, provided, respectively, with drive-wheels *r²*, *H'*, *n³*, *o²*, and *p²*, and a single endless drive-chain, *R*, running around said drive-wheels, whereby all of said parts are driven by a single chain, substantially as set forth. 125

Witness my hand this 13th day of September, 1883.

FREDERICK W. HOWELL.
